UNITED STATES PATENT OFFICE.

ROMAN ABT, OF PARIS, FRANCE.

PERMANENT WAY FOR MOUNTAIN RAILWAYS.

SPECIFICATION forming part of Letters Patent No. 284,790, dated September 11, 1883.

Application filed February 5, 1883. (No model.) Patented in Germany November 30, 1882; in France December 16, 1882, No. 152,677, and in Italy March 31, 1883, XVI, 14,971, and XXX, 32.

To all whom it may concern:

Be it known that I, ROMAN ABT, a citizen of Switzerland, and a resident of Paris, France, have invented certain Improvements in Permanent Ways for Mountain Railways, of which the following is a specification.

My invention relates to certain improvements in the construction of the racks or toothed rails of inclined railways, as more fully described hereinafter.

In the accompanying drawings, Figure 1 is a transverse section of my improved toothed rail. Fig. 2 is a transverse section of a modification; Fig. 3, a transverse section of a further modification; Fig. 4, a side view of the compound rail shown in Fig. 1; Fig. 5, a transverse section of a railway provided with my improved rack-rail.

My improved rack-rail, into which the toothed driving-wheel on the locomotive is intended to gear to draw the train up the inclined railway, is intended to be laid midway between the usual smooth rails, as shown in Fig. 5. Instead of being made in one piece, as usual, it is made up of two or more rack-bars, A A' A'', supported at intervals on and bolted to flanged supports or chairs B B, as shown in Figs. 1, 2, and 4. The teeth of these rack-bars, instead of being of the usual gear shape, are wedge-shaped, tapered upward, as shown in Fig. 4, and the bars are spaced apart, Figs. 1 and 2, and so arranged in relation to each other that the teeth of the several bars are out of line with each other, as indicated in Fig. 4. The lengths of the several

bars are also preferably arranged so as to break joints. Where the joints occur, the bars are united by bolts and a suitable fish-plate, b, Fig. 4, in any convenient way. The rack-bars A A' may themselves be flanged, as shown in Fig. 3, if desired.

The setting of the teeth of the compound rack-rail out of line with each other insures the direct engagement of the corresponding toothed drum on the locomotive, so that this drum may be driven direct from the engine and intermediate transmission-wheels dispensed with. It also admits of a rate of travel as high as twenty-five kilometers per hour without affecting the smooth running of the train.

I claim as my invention—

1. A compound rack-rail for inclined railways, composed of a number of united bars having their teeth arranged out of line with each other.

2. A compound rack-rail composed of a number of united bars having tapering or wedge-shaped teeth.

3. The combination of flanged chairs with a compound rail composed of rack-bars A A', spaced from each other.

In testimony whereof I have signed my name to this specification in the presence of two subscribing witnesses.

R. ABT.
